UNITED STATES PATENT OFFICE.

CHARLES HULTGREN, OF CHICAGO, ILLINOIS, ASSIGNOR TO S. KARPEN & BROS. OF CHICAGO, ILLINOIS, A CORPORATION OF WEST VIRGINIA.

SOFA BED.

Application filed April 4, 1921. Serial No. 458,189.

To all whom it may concern:

Be it known that I, CHARLES HULTGREN, a citizen of the United States, residing at Chicago, in the county of Cook and State 5 of Illinois, have invented a new and useful Improvement in Sofa Beds, of which the following is a specification.

The present invention relates particularly to sofa-beds of the type in which the 10 cushions of the sofa are adapted to be spread on the bed-sections in the extended condition of the structure to serve as a mattress for the bed. The invention is in the nature of a modification of or an improvement upon 15 the invention set forth in my application No. 444,724 filed February 14, 1921.

The primary object of the present invention is to provide a construction of the character set forth in my pending application 20 in which the bed structure is readily demountable from the main frame.

The invention is illustrated in its preferred embodiment in the accompanying drawings, in which—

25 Figure 1 represents a vertical sectional view of the structure in extended condition, the section being taken as indicated at line 1 of Fig. 4; Fig. 2, a similar sectional view, but showing the structure in folded, or sofa, form; Fig. 3, a broken front elevational view of the structure in sofa form, the front piece with which the front bed-section is provided being removed, however; Fig. 4, a broken plan section of the sofa-bed in open 30 condition; Fig. 5, an elevational view showing one of the demountable bars having permanently pivoted thereto the levers which carry the bed-sections, it being understood that such an arrangement is employed at each 35 end of the sofa-bed structure; Fig. 6, a view of one of the supporting plates or bars with which the end standards of the main frame are equipped; Fig. 7, a broken sectional view taken as indicated at line 7 of Fig. 4; and 40 Fig. 8 a broken sectional view taken as indicated at line 8 of Fig. 1.

In the embodiment shown, A represents a main frame provided with a back A', end standards or arms A², and front and 45 rear cross members A³ and A⁴ extending longitudinally of the main frame and connecting the base portions of the end standards; B, a front bed-section which, in the folded condition of the structure, is super- 50 posed over the rear section and becomes the

seat portion on which the cushions are supported; C, a rear bed-section which is adapted to be lowered in the frame when the structure is converted to sofa form; B', a front mattress-section and C' a rear mattress-section supported by the bed-sections B and C respectively, the section C' being adapted to fold forwardly upon the section B' about the point or line 1, preparatory to converting the structure to sofa form; D, D', pairs of parallel front and rear levers fulcrumed on demountable bars employed; E, a demountable bar at each end of the structure, each of said bars carrying a front lever and a rear lever; and F a supporting 60 bar permanently secured to the inner surface of each of the end standards A², said supporting bars F carrying the demountable bars E.

The frame A may be of any suitable construction and design. It is shown as comprising substantial end standards or arms which are rigidly connected at the back portions by the back A', the lower portions of the end standards being staunchly connected 65 together by the rails or stringers A³ and A⁴. The main frame is preferably equipped with casters 2.

The frames of the bed-sections B and C are similar in construction, but the front 70 section B is preferably slightly longer than the rear section C, as will be understood from Fig. 4. The front bed-section comprises a lower rectangular frame 3, an upper U-shaped frame 4, and corner pieces 5 rising 75 from the lower frame and supporting the upper frame. Similarly, the rear bed-section C comprises a lower frame 6, an upper frame 7, and corner pieces 8 rising from the lower frame and supporting the upper 80 frame.

The upper frames 4 and 7 of the bed-sections serve to support the wire mattress, or mattress sections 9, which may be stretched thereon. The wire mattress serves 85 to support the cushions or mattress sections B' and C'. Any suitable spring construction may be substituted for the wire mattress 9. The end members of the upper frames 4 and 7 are suitably trussed or braced 90 by means of braces 10 which connect said end members with the longitudinal members of the lower frames.

As shown in Fig. 1, the rear corner pieces, or standards 5 of the front bed-section and 110

the front corner pieces or standards 8 of the rear bed-section are inclined rearwardly and upwardly, so that the front bed-section is somewhat wider (from front to rear) than the rear bed section. Thus, when the front bed-section occupies the folded condition shown in Fig. 2, thus serving as a seat, the rear edge of the seat thus afforded extends backwardly under the padded or cushioned portion of the back A'. Moreover, by inclining the adjacent edges of the frames of the bed-sections in the manner shown in Fig. 1, the front section will more readily clear the rear section in the operation of converting the structure from bed form to sofa form.

The levers employed are of angular form, the elbow portions of the front levers being pivotally connected with the front portions of the demountable plates E by means of rivets 11, and the elbow portions of the rear levers being pivotally connected with the intermediate portions of the plates E by rivets 12. Each lever has a forwardly extending long arm 13 which inclines upwardly somewhat as shown in Fig. 1, and has an upstanding short arm 14. The long arms of the front levers D are connected with the end members of the lower frame of the bed-section B by pivots 15; and the long arms of the rear levers are connected with the squared ends of a longitudinal rod 16 whose end portions are journaled in the end members of the lower frame 3 of the front bed-section in the manner illustrated in Fig. 8. The short arms of the front levers D are connected with the front portions of the end members of the lower frame of the rear bed-section C by pivots 17; and the short arms of the rear levers D' are connected with the intermediate portions of the end members of the lower frame 6 of the rear bed-section by pivots 18.

By comparing Fig. 1 with Fig. 2, it will be observed that in converting the structure from bed-form to sofa form, the levers are turned approximately 180° about the fulcrums 11 and 12, and the rear bed-section is lowered in the main frame, while the front bed-section is carried to a position in which it is superposed over the rear bed-section.

The supporting plates F are provided with perforations 19 adapted to receive screws by means of which the plates are firmly secured to the inner surfaces of the lower portions of the end standards A'. The plates F have inwardly struck portions 20 which are provided with angular slots 21. These slots are adapted to receive outwardly extending studs 22 which are securely riveted to the demountable plates E, as appears from Fig. 7. The outer ends of the studs 22 are equipped with flanges or heads 22a which are received in the spaces between the offset portions 20 of the bars F and the inner

surfaces of the end standards A'. Each of the supporting plates F is equipped with a latch or locking pawl 23 which is adapted to extend across the front slot 21. The pawls 23 are connected with the plates F by pivots 24. Each pawl is notched to engage the corresponding stud 22. The purpose is to confine the studs 22 in the bays or offsets 21a of the slots 21, as will be readily understood from Figs. 6 and 7.

When desired, the pawls 23 may be thrown back; and the bed structure may then be lifted from the main frame.

The main frame A may, if desired, be made of knock-down construction. This is not illustrated, however.

By means of the construction described, the metal bed structure may be assembled with the various members permanently connected; and the bed structure may readily be inserted into the main frame of the sofa-bed after shipment to the dealer.

It is desirable to provide counterbalancing means which will aid in the operation of converting the structure from bed form to sofa form and vice versa. For this purpose, the demountable plates E are provided with rearward extensions E' having their rear extremities bent inwardly as indicated at 25. Substantial coil springs 26 connect the members 25 with the end members of the rear bed-section. It will be understood from Figs. 1 and 2 that the springs 26 are placed under tension when the structure is in either the extended condition or the folded condition. Thus, the springs will aid the operator in converting the structure from one form to the other form.

The front bed-section B is equipped at its front portion with legs 27 which are adapted to rest upon the floor in either the extended condition or the folded condition of the device. The front edge of the front bed-section is also equipped with a front piece 28 which is adapted to conceal the bed structure when it is in the folded condition. The ends of the front piece 28, it will be understood, are disposed adjacent the inner surfaces of the front portions of the standards A' of the main frame when the structure is in sofa form.

The foregoing detailed description has been given for clearness of understanding only, and no unnecessary limitations should be understood therefrom, but the appended claims should be construed as broadly as possible in view of the prior art.

What I regard as new and desire to secure by Letters Patent, is:

1. In a structure of the character set forth the combination of a main frame having end standards provided at their inner surfaces near their lower edges with rigidly secured supporting plates, a pair of plates demountably carried by said supporting plates and

- equipped with rearward extensions, a pair of levers permanently pivoted to each demountable plate, each of said levers having a long arm and a short arm, a front bed-section mounted on the long arms of said levers, and a rear bed-section mounted on the short arms of said levers, the short arms of said levers serving to carry the rear bed-section rearwardly a substantial distance 5 and then forwardly substantially the same distance in the operation of folding the structure, said rear bed-section being adapted to occupy a position above the plane of said extensions when the bed is open and a position 10 below the plane of said extensions when the bed is closed, and springs connecting the rear ends of said extensions with the rear bed-section.
2. In a structure of the character set forth 15 the combination of a main frame having end standards equipped at the lower portions of their inner surfaces with rigidly secured horizontal bars, each of said bars having a plurality of inwardly struck offset portions 20 provided with slots opening at their upper edges, a pair of horizontally disposed demountable bars each equipped with a plurality of outwardly extending studs received by said slots, a pair of angular levers having 25 their elbow portions permanently mounted pivotally on each demountable bar, each of said levers having a long arm and a short arm, a front bed-section carried by the long arms of said levers, and a rear bed-section 30 carried by the short arms of said levers.
3. In a structure of the character set forth 35 the combination of a main frame having end standards, front and rear bed-sections, a pair of parallel levers of angular form, each lever having a long arm pivotally connected with 40 the front bed-section and a short arm pivotally connected with the rear bed-section, said short arms being adapted to carry the rear bed-section rearwardly a substantial distance and then forwardly a substantial distance in the operation of folding the structure, a pair of demountable bars upon which the elbow portions of said levers are permanently fulcrumed, each of said bars having a rearward extension, springs connecting said extensions with the rear bed-section, and supporting bars rigidly secured to the inner surfaces of the lower portions of said end standards, said supporting bars having slotted inwardly offset portions, and said demountable bars having outwardly extending studs engaging the slotted offset portions of the supporting bars, said rear bed-section being adapted to be disposed above the plane of said extensions in the 45 open position and below said plane in the folded position of the structure.
4. In a structure of the character set forth the combination of a main frame having end standards provided at their inner surfaces 50 near their lower edges with rigidly secured supporting plates, a pair of plates demountably carried by said supporting plates and equipped with rearward extensions, a pair of levers permanently pivoted to each demountable plate, each of said levers having a long arm and an offset short arm, the long arms of the rear set of levers being adapted to swinging past the upper ends of the short arms of the front levers when the structure 55 is converted to bed form, a front bed-section mounted on the long arms of said levers, and a rear bed-section mounted on the short arms of said levers, and springs connecting the rear bed-section with the rearward extensions of said demountable plates.

CHARLES HULTGREN.
